UNITED STATES PATENT OFFICE.

EDWARD M. SPENCE, OF LYNN, MASSACHUSETTS, ASSIGNOR TO UNITED SHOE MACHINERY CORPORATION, OF PATERSON, NEW JERSEY, A CORPORATION OF NEW JERSEY.

EDGE-FINISHING MACHINE.

Application filed June 7, 1926. Serial No. 114,199.

This invention relates to machines in which a hot shrinking tool is employed for finishing the edges of pieces of sheet material and is herein illustrated as embodied in a machine for finishing the edges of pieces of upper leather which are to be used in the manufacture of boots and shoes.

Machines of this general type commonly comprise a support for a leather piece, a plow or turning post, a heated tool spaced somewhat from the operative face of the turning post and means for feeding the leather over the support with the display side of the leather (usually the grain side) in contact 10 with the support and with the extreme margin of the other side (usually the flesh side) held up against the hot shrinking tool whereby the margin of the flesh side is shrunk and the margin of the grain side caused to curl 15 with the support and with the extreme margin of the other side (usually the flesh side) held up against the hot shrinking tool whereby the margin of the flesh side is shrunk and the margin of the grain side caused to curl 20 toward the flesh side, so that in the finished work the edge presents a grain surface instead of the flesh surface which resulted when the leather piece was originally cut out of the skin, a hammer being commonly employed which strikes the edge to increase the 25 curl thereof.

With certain kinds of work it has been found desirable to skive the edge before presenting the work to the machine; but whether 30 the work is skived or unskived, the edge of the work—or a portion of the edge—is bent up between the shrinking tool and the turning post and, as has been stated, is operated upon by the hammer, the amount of stock which is 35 finally bent down by the hammer depending upon the amount which extends up between the turning post and the tool.

The general object of the present invention is to improve still further machines of this 40 general type so as to facilitate operating upon a greater variety of unskived work and to ensure that the width of the curled edge shall be uniform.

According to one feature of the present invention, a recess is provided in the tool which is located partly in that face of the tool which is opposite the work support and partly in a face which forms an angle with the first-named face. In the illustrated embodiment 45 of the invention this recess takes the form of a groove which extends from the forward end of the tool along the bottom thereof and then up and across a portion of that side of the tool

which is adjacent to the turning post, the groove being comparatively deep and wide 55 at its front end and becoming narrower and shallower as it progresses. In the operation of the machine the work is fed through this groove, that portion of the groove which is in the bottom of the tool serving as a stop to 60 limit the extent to which the edge of the work may be bent up while the portion of the groove in the side of the tool provides space into which the edge may curl, the general extent of the groove, due in part to the spiral turn 65 which it makes, facilitating the proper curling of the edge.

These and other features of the invention, including certain details of construction and combinations of parts, will be described 70 as embodied in an illustrated machine and pointed out in the appended claims.

Referring now to the accompanying drawings,

Fig. 1 is a perspective of a portion of a machine in which the present invention is embodied;

Fig. 2 is a perspective of the shrinking tool;

Fig. 3 is a vertical section through a portion of the machine on the line 3—3 of Fig. 2 showing a piece of work in process of being operated upon;

Fig. 4 is a similar section on the line 4—4; and

Fig. 5 is a cross-section of a piece of work 85 after it has been operated upon.

Figures 3 to 5 inclusive are shown upon exaggerated scales.

The illustrated machine is similar in its general organization to the machine of Letters Patent No. 1,599,518, granted Sept. 4, 1926, upon an application filed in the name of Fossa, and reference is made to that application for details of construction not described below.

The work is fed intermittently over a table 5 in the direction indicated by the arrow in Fig. 1 by an upper feed member 7, a lower feed member 9 and a hammer, not shown. The lower feed member moves back and forth. The upper feed member and the hammer describe rectangular paths in a vertical plane. The leather piece rests with its grain side upon the table 5 and upon the lower feed member 9, with its margin bent upwardly 105 and in contact with a turning post 11. Lo-

cated adjacent to the turning post is a shrinking tool 13, being herein shown as a generally U-shaped member of suitable metal such, for example, as the alloy known as ni-chrome, heated to the desired temperature by an electric current. This temperature is varied according to the nature and weight of the leather being operated upon, but in any case is maintained sufficiently high to sear and shrink the leather on one side so that the unshrunken side will curl toward the shrunken side. The lower side or bottom of the shrinking tool is inclined downwardly to the plane of the table from front to rear, as shown in Fig. 1; and the side of the tool adjacent to the turning post is inclined slightly away from the post from front to rear, the forward portion of the tool being close to the post, as shown in Fig. 3, and the rear portion being slightly spaced from the post, as shown in Fig. 4. This spacing has been considerably exaggerated in the figures since it could not otherwise be shown. The actual distance from the rear of the tool to the post is in the neighborhood of .003 of an inch. As the leather passes beneath the tool, it is shrunk on the flesh side so that the grain side curls toward the flesh side, the hammer descending at the proper time upon the curled edge.

The illustrated shrinking tool is provided with a recess in the form of a groove having a portion 15 located in the bottom of the tool and a connecting portion 17 located in that side of the tool which is adjacent to the turning post. This groove starts at the forward end of the tool and is deepest at that point. The portion 15 is V-shaped in cross-section as best shown in Fig. 3. The inner wall of the portion 15 terminates in a thin edge 18, which is substantially parallel to the plane of the inner side of the tool. The edge 19 of the outer wall of the portion 15 of the groove extends somewhat obliquely from front to rear of the tool so that the portion 15 is wide at its forward end and grows progressively narrower toward its rear. This portion is also deep at its front end and grows progressively shallower toward the rear. By providing the portion with this shape, several advantages are attained. The leading end of the edge of the work may be readily presented to the groove, and the groove at that locality is shaped to fit around the flesh corner of the edge as shown in Fig. 3. As the work is fed along, the flesh is shrunken and probably to some extent burned away, so that its size decreases, the decreasing size and width of the groove being provided because of this decrease in the dimensions of the edge. The edge is thus shrunk to a great extent by the time it reaches the quarter or spiral turn of the groove through which it passes to the position shown in Fig. 4. In this position the edge of the work extends into the portion 17 of the groove, being bent about the lower

wall 21 of the portion 17. This thin wall 21 projects into the concavity of the curved edge and applies heat to this locality to cause a final shrinking effect. The turning post 11 terminates at the rear end of the shrinking tool, and the hammer, which has been referred to above, descends just behind the turning post and the shrinking tool to hammer the edge, which is at that time somewhat plastic, into the approximate position shown in Fig. 5.

The tool of a machine of this general type is maintained, during its operation upon the work, at such a high temperature that it is liable to be bent sidewise if any considerable force is exerted upon it which tends to produce such a bending. It should be noted, in this connection, that the portion 15 of the groove in the tool is V-shaped in cross-section with its walls making equal angles with the vertical. Consequently, as the leather passes through this portion of the groove, whatever forces the leather may there exert sidewise of the tool are equal and opposite so that there is no tendency to bend the tool to one side.

The width of the edge of the leather which is permitted to be bent up is limited by the engagement of the leather with the portion 15 of the groove so that this width is substantially uniform; and the whole groove, owing to its spiral turn, facilitates the proper curling of the edge.

Although the groove has been illustrated as being of a particular shape and location, it should be understood that the invention is not limited in its broader aspects to this particular groove.

Having thus described my invention, what I claim as new and desire to secure by Letters Patent of the United States is:

1. A machine of the class described having, in combination, a shrinking tool, and means for causing the tool to operate upon the work to curl the edge thereof, said tool having a recess adapted to receive the edge of the work, one part of said recess being located in the under face of the tool and another part in its side.

2. A machine of the class described having, in combination, a support for the work, a shrinking tool, and means for causing the tool to operate upon the work to curl the edge thereof, said tool having a recess to receive the edge, one part of the recess being located in that face of the tool which is adjacent to the support and another part in a face which forms an angle with the first-named face.

3. A machine of the class described having, in combination, a shrinking tool, and means for causing the tool to operate upon the work to curl the edge thereof, there being in the tool a groove adapted to receive the edge of the work, said groove extending along the under face of the tool from the forward end of the

tool to a locality near the rear end and there making a turn so that a rear portion of the groove is in the side of the tool.

4. A machine of the class described having, in combination, a support for the work, a shrinking tool, and means for feeding the work over the support with its edge portion in contact with the tool, said tool having in its bottom a groove part of which decreases in size from front to rear to provide for the shrinking of the edge portion of the work and part of which lies in the side of the tool to aid in curling the shrunken edge.
5. A machine of the class described having, in combination, a support for the work, a shrinking tool, and means for feeding the work over the support with its edge portion in contact with the tool, said tool having in its bottom a groove part of which decreases in size from front to rear and part of which lies in the side of the tool, the bottom part serving as a stop to limit the extent to which the edge portion of the work may bend upwardly and the side portion serving to impart a curl to the shrunken edge.
6. A machine of the class described having, in combination, a support along which the work is fed, a shrinking tool, and a co-operating turning post, there being formed in the tool a groove to receive the edge of the work shaped to guide the edge first in a path located between the tool and the support and then in a path extending in a different direction and located between the tool and the turning post.
7. A machine of the class described having, in combination, a support along which the work is fed, a shrinking tool, and a co-operating turning post located adjacent to the inner side of the tool, there being in the tool a groove comprising a portion located in the bottom of the tool, another portion located in

the inner side of the tool and a curved connecting portion.

8. A shrinking tool for a machine of the class described having a groove adapted to receive the edge of the work, said groove extending from the front thereof along the bottom to a locality near the rear and there making a curved turn up across a portion of a side thereof.

9. A shrinking tool for a machine of the class described having a groove part of which is located in the bottom and part in the side thereof, the part in the bottom decreasing in depth and width from front to rear of the tool.

10. A shrinking tool for a machine of the class described having a groove part of which is located in the bottom and part in the side thereof, the part in the bottom being V-shaped in cross-section and decreasing in depth and width from front to rear of the tool.

11. A tool for shrinking the margin on one side of a piece of sheet material such as leather in such manner as to cause the unshrunken side to curl toward the shrunken side, said tool having in it a recess to receive the curled edge, one part of said recess being located in the bottom of the tool and another part in the side thereof.

12. A tool for shrinking the margin on one side of a piece of sheet material such as leather in such manner as to cause the unshrunken side to curl toward the shrunken side, said tool having in it a recess to receive the curled edge, said recess extending along its bottom and across a portion of its side.

In testimony whereof I have signed my name to this specification.

EDWARD M. SPENCE.
